(57) **CLAIM**

The ornamental design for a cup carrier, as shown and described.

DESCRIPTION

FIG. 1 is a perspective view of a cup carrier showing the new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The dash-dash type broken lines shown in the drawing views are included for the purpose of showing environmental subject matter. The dash-dot-dash type broken lines shown in the drawing views define the bounds of the claim. The broken lines form no part of the claimed design.
